(57) **CLAIM**

The ornamental design for a water tank for use in water supplying machine for endoscope, as shown and described.

DESCRIPTION

FIG. 1 is a perspective view from upper and right side of a water tank for use in water supplying machine for endoscope, showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a cross-sectional view of 8-8 line in FIG. 6 thereof; and,

FIG. 9 is a cross-sectional view of 9-9 line in FIG. 6 thereof. The broken lines shown in the drawing depict portions of the water tank for use in water supplying machine for endoscope that form no part of the claimed design. The dot-dashed lines show the boundary of the claimed design and form no part of the claimed design.
